United States Patent Office.

J. FRANKLIN MASON, OF BENTONSPORT, IOWA.

Letters Patent No. 65,101, dated May 28, 1867.

IMPROVEMENT IN BRIDLES.

The Schedule referred to in these Letters Patent and making part of the same.

TO ALL WHOM IT MAY CONCERN:

Be it known that I, J. FRANKLIN MASON, of Bentonsport, Van Buren county, in the State of Iowa, have invented a new and improved Bridle for Horses; and I do hereby declare that the following is a true and exact description of it, reference being had to the accompanying drawing, and the letters of reference marked thereon.

The invention consists, first, in the use of a rounded leather strap, A, of a suitable size and length to answer as a bit, terminating in an extended flat strap, E, at either end. These flat straps are doubled through a slot in the guards C C, forming loops in which are inserted the rings R R for attaching the driving-lines. One of these flat straps E E is furnished with a buckle, having a pad, D, underneath it, which, by pressing against the animal's lower jaw, keeps the bit in place when once secured by buckling. The combination of the round and flat straps with guards and rings forms a complete bridle without the use of a head-stall.

Its operation is as follows: The round strap or bit A is placed in the mouth back of the bridle teeth, so called, and secured in this position by buckling the straps E E together underneath the lower jaw.

I claim as my invention—

The rounded strap, in combination with guards and rings, to be secured to the horse's under jaw, in the manner and for the purpose herein described.
